TYPEWRITING MECHANISM

Samuel Brand, Binghamton, N. Y., assignor to
 International Business Machines Corporation,
 New York, N. Y., a corporation of New York

Application August 15, 1939, Serial No. 290,277

5 Claims. (Cl. 197—66)

This invention relates to improvements in typewriting machines, and the principal object of the invention is the provision of a device for initiating an operation of the carriage return mechanism by the operation of a type bar operating mechanism.

Another object of the invention is the provision of means for printing a symbol and initiating a carriage return operation by the depression of a single key.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a fragmentary section through the typewriter.

Fig. 2 is a detailed view of the symbol type bar operating cam and the carriage return cam.

Fig. 3 is a plan view of the power drive roller and the type bar and carriage return cams.

Fig. 4 is a section taken on line 4—4, Fig. 2, and showing the carriage return operating cam.

Fig. 5 is a fragmentary front illustration of the power devices for controlling and driving the carriage return mechanism.

Fig. 6 is a fragmentary rear elevation of the machine showing the carriage return.

Fig. 7 is a modified form of the mechanism shown in Fig. 2.

Fig. 8 illustrates the offset type to provide a space from the last character in the line.

Referring to the drawings, the invention is shown applied to a power driven typewriter of a well-known type, although its use is not limited to such machines. The illustrated machine includes a type bar 1, (Figs. 1 and 8) carrying types 2, and being pivoted in a type basket 3 (Fig. 1) for movement to and from printing engagement with a platen 4. A toggle lever 5 pivoted to the type bar has one arm pivoted to a toggle arm 6, which is pivoted to a fixed part. The other arm of the lever 5 is operatively connected to one arm of a bell crank 7 by means of a link 8. The bell crank 7 is pivotally mounted on a common pivot rod 8a and is resiliently retained in its normal position with the type bar retracted by a spring 9. The other arm of the bell crank 7 is connected with an arm of a power operated lever 11 by a link 12. The other arm of the lever 11 projects downwardly adjacent a power driven roller 13 and carries a cam 14 rotatably mounted thereon.

The cam 14 is normally out of engagement with the power driven roller, but is resiliently urged into engagement therewith by a spring pressed arm 15 pivotally carried by the lever 11 and engaging a projection 16 on the cam. A stop 17 on the lower end of a lever 18 pivotally mounted on the lever 11 engages a projection 19 on the cam 14, thus holding the cam against the action of the spring pressed arm 5.

10 At its upper end the lever 18 carries a projection which is straddled by the lower end of an arm 20 projecting downwardly from a key lever 21 pivoted on the rod 8a. The key lever 21 carries at its free end a key 22, whereby it may be manually operated.

Operation of the key 22 rocks the lever 18 to withdraw the stop 17 from the projection 19, whereupon a spring pressed arm 15 rocks the cam 14 into contact with the periphery of the power driven roller 13. The cam is then rotated by the roller and swings the lever 11 pivoted on a rod 11a to actuate the bell crank 7, which swings the type bar 1 into engagement with the platen.

20 A key controlled power driven means is provided for returning the carriage against the action of the usual spring drum (not shown) to begin a new line. This means includes the power roller 13 with which cooperates a key controlled cam 23 of the usual well-known construction. The cam 23 is mounted on a lever 24 (Fig. 4), one arm of which is connected by a link 25 to one end of a toggle lever 26 (Fig. 5) pivotally mounted on a bracket 27 fixed on the frame of the machine. The toggle lever 26 projects through an opening in the frame and is connected at its outer end to one end of a toggle link 28, the other end of which is connected to a rod 29 adjustably mounted in the upper end of a yoke 30 loosely mounted on a stud 31 projecting from the frame of the machine.

25 The parts are normally in their inoperative position as shown in Fig. 5, but upon depression of the carriage return key 32 a lever 33 releases the cam 23, which is moved into engagement with the power roller 13 and is actuated in a well-known manner to straighten the toggle 26—28, which through the yoke 30 controls a clutch member 33, mounted on the shaft 34 of the power roller 13 adjacent a spool 35 freely mounted on the shaft 34. A tape 36 is wound on the spool 35 and has one of its ends secured to the core of said spool. The other end of tape 36 passes over a pulley (not shown) arranged on 30 the frame end of the carriage guideway and at

its other end is engaged with a hook 37 projecting from the carriage.

The clutch member 33 is mounted to rotate with the shaft 34 and is movable axially thereon into engagement with the spool 35 to connect said spool to the shaft so that it may be driven thereby. This engagement of the clutch member 33 with the spool 35 is effected by straightening of the toggle 26-28 as set forth above and the tape is thus wound on the spool to return the carriage to begin a new line. The construction of the clutch is clearly disclosed in Patent No. 1,753,450, granted April 8, 1930, to Russell G. Thompson, to which reference may be had for complete description thereof.

It is sometimes desirable to insure the printing of a symbol on the end of a typed line, for instance, in certain types of justification it is essential to sense the length of each line to determine the amount of justification required. This sensing is facilitated by printing a symbol or mark at the end of the line which may be more accurately sensed than the last printed letter or figure.

One of the important features of the instant invention, therefore, is the provision of the following described device to automatically print such a symbol and initiate a carriage return action by the depression of a single key.

The levers 11 and 24 which carry the cams 14 and 23 respectively are mounted adjacent each other on the rod 11a. A stud 39 (Figs. 2 and 3) on the lever 11 which carries the symbol cam 14 cooperates with an ear 40 projecting from the lever 38 associated with the carriage return cam 23. Referring to Fig. 3 it can be seen that with the cams 14 and 23 in their normally latched positions there is a space between the stud 39 and ear 40.

As set forth above, depression of the symbol key 22 releases the cam 14, which, upon coming into contact with the power roller 13, is operated to throw the symbol type bar against the platen 4 to make the impression. Just before the type bar completes its printing stroke, the stud 39 engages the ear 40 actuating the lever 38 to release the carriage return cam 23. This cam coming into contact with the power roller 13 is then actuated to operate the carriage return clutch in the manner above described.

The symbol key 22 and the carriage return key 32 may be rigidly connected as illustrated to operate as a unit, or the key 22 and its corresponding key stem may be omitted, in which case the operator, when the end of a line is reached, depresses the carriage return key 32, which effects an operation of the symbol type bar and initiates a carriage return action.

Obviously the carriage return key 32 and its stem may be eliminated and the operator, upon reaching the end of a line, may depress the symbol key 22 with the same result.

Also, the carriage return key 32 may be arranged as shown in Fig. 7 to trip its cam 23 independently of the symbol key 22, by which arrangement the symbol may be printed and the carriage returned in timed relation by manual depression of a single key, namely the symbol key 22, and the carriage may be returned independently of the symbol key without printing the symbol by depressing the carriage return key.

While there has been shown and described and pointed out the fundamental novel features of the invention as applied to a single modification it will be understood that various omissions and substitutions and changes in the form and de-

tails of the device illustrated and in its operation may be made by those skilled in the art without departing from the spirit of the invention. It is the intention, therefore, to be limited only as indicated by the scope of the following claims.

What is claimed is:

1. In a typewriting machine, the combination of a frame, a carriage movable transversely thereon, a type bar, a lever connected with said type bar, a power roller, a cam element carried by said lever and capable of engagement with the power roller, key controlled means for effecting the engagement of the cam element with the power roller to cause movement of the lever to actuate the type bar, power operated means to move the carriage to begin a new line, and means carried by said lever for effecting an operation of the power operated means upon movement of said lever during the actuation of the type bar.
2. In a typewriting machine, the combination of a frame, a carriage movable thereon, a type bar, a lever connected with said type bar, a power driven roller, a cam carried by said lever and movable into engagement with the roller for imparting movement to the lever to actuate the type bar, key controlled means to control the engagement of said cam with said roller, carriage return means, a lever connected to said carriage return means, a second cam carried by the latter lever and movable into engagement with the roller to effect operation of said carriage return means, and means carried by the first mentioned lever to control the engagement of the second cam with the roller upon engagement of the first mentioned cam with said roller.
3. In a typewriting machine, the combination of a frame, a carriage movable thereon, a type bar, a power driven roller, a cam and a carrier for said cam, the carrier being connected to the type bar, means biasing said cam toward engagement with the power roller, a latch normally holding said cam out of such engagement, key controlled means to operate said latch to release the cam for engagement with the aforesaid roller to cause movement of the carrier for effecting operation of the type bar, carriage return means, a second cam, and means normally biasing the second cam into engagement with the power roller, a carrier for said second cam having connection with said carriage return means for operation of the latter means upon engagement of the second cam with the roller, a latch associated with said second cam for normally holding the latter cam out of such engagement, and a projection on the carrier for the first mentioned cam for actuating the second mentioned latch upon engagement of the first mentioned cam with the power roller.
4. In a machine of the class described, recording elements, a power operator, devices having linkage connection with the recording elements and being engageable with the power operator for operating said elements to effect recording on a sheet, selectively operable means for causing said devices to engage the power operator for operation thereby, a carriage for the record sheet, power means to return said carriage, an element having linkage connection with said carriage return means and being engageable with the power operator for causing operation of the carriage return means, a latch normally restraining said element from such engagement, and means carried by the linkage connection of one of said devices and actuated upon operation of said device by the power operator to release

the engageable element from the latch for engagement with the power operator.

5. In a machine of the class described, type elements, a power operator, a plurality of cams engageable with the power operator; a carrier for each of said cams, each carrier having a connection with one of said type elements for operating the type element to print on a record sheet upon the engagement of the associated cam with said operator; key controlled means for selecting said cams for engagement with the power operator, a carriage for the record sheet, power

means to return said carriage, another cam engageable with the power operator; a carrier for the latter cam, said last named carrier having a connection with the carriage return means to effect operation of the power carriage return means upon engagement of said latter cam with the power operator; and means on the carrier for one of the first mentioned cams and actuated upon operation of said cam by the power operator to cause the cam related to the carriage return means to also engage the power operator.
